ACTION ZONE GIRDLE

This invention is an improved girdle in which a relatively narrow "action" lying along the natural crease lines of the wearer's body is capable of stretching vertically more easily than the portions of the girdle which are higher and lower than the action zone.

It is a matter of record that the female form of the human species is enhanced in appearance by girdles that are constructed with areas of little stretchability and areas of more stretchability. Difficulties are encountered in doing this however because certain parts of the body require more restriction than others and because different parts of the body elongate more than others; as for example the area from the back waist down to the buttocks when the wearer sits.

Panty girdles in particular are subject to such difficulties because of the need for greater control and less movement in the torso-encircling part and for relatively less control and more ease of movement in the leg parts of the girdle.

The present invention provides the desired combination of greater control and less movement in the upper body-encircling part of the girdle with lesser control and more freedom of movement in the leg portions of the girdle.

I obtain this desired combination by separating the upper part of the girdle from the lower part with a relatively narrow zone of material that stretches vertically more easily than either the higher or lower part of the girdle. I call this the action zone.

By means of my new construction each leg can move independently without placing undue stress on the other leg or on the upper part of the girdle. As the wearer moves about or engages in exerative movement the generated stresses are generally responded to first by the action zone and this minimizes the tendency of the upper or lower part of the girdle to become displaced. In a conventional girdle the upper and lower parts are usually integral with each other and movement of one will cause movement in the other. Thus stress which lowers the back waistline of a conventional girdle will also often cause the bottom part to move up. This undesirable vertical displacement of the top and bottom edges of the girdle is minimized by my invention which tends to keep the top part from coming down and the bottom part from coming up. The ability of my new girdle to resist such displacement contributes to the comfort of the wearer.

The upper more restrictive part of the girdle can be made of conventional materials and follow conventional practice. It can have front, back and side panels of varying stretch characteristics as is known in the girdle art. The lower part of the girdle can also be conventional and can take shape as the legs of a panty girdle or as the lowermost part of an open bottom girdle. The materials of which the girdle can be made include stretchable fabrics whether based on elastomers or not, and elastomeric substances per se such as dipped latex, sheet rubber, etc. and their equivalents, and in fact any material which is conventionally used in the manufacture of girdles.

The action zone of my new girdle can be a material of any kind so long as it has the desired characteristics. It can be cloth that is woven, knit, or made on a Jacquard bobbinette machine. Examples of suitable cloth materials include stretchable fabrics such as elastic leno, elastic tricot, stretch lace, stretch net, spandex fabrics including spandex mesh and power net, Jacquard bobbinette, open network fabrics positioned on the bias, and their equivalents. Rubber lace, rubber net and similar elastomeric materials may also be used. Action zone material having all-way stretch is generally most satisfactory. One suitable fabric is spandex mesh fabric having elastomeric threads running in one direction only and which will elongate and recover in both directions.

By easier stretchability I mean the action zone material will stretch vertically first before the upper and lower parts of the girdle when it is subjected to a vertically directed stretching force. It should be noted that generally the action zone will stretch in the circumferential direction just about as easily as the adjacent upper and lower parts of the girdle. This is neces-

sary of course for the garment to be a proper girdle. It is in the vertical stretch direction that the action zone material differs most greatly. Easier stretchability can be determined by measuring the amount of force needed to elongate the material to a given distance. Where one piece of cloth requires a force of about 3 lbs. to elongate it 60 percent of its original length and a second piece of cloth requires about 3½ lbs. for the same elongation, the first piece obviously is the easier one to stretch.

10 The action zone should be positioned in a particular way. It should lie along the natural crease lines between the legs and the trunk of the wearer in the front, which may be referred to as the groin lines, and under the buttocks of the wearer in the rear. These appear to be movement areas where stresses generated by body movements readily show up in a girdle. By making the action zone from material that is most easily stretchable the other parts of the girdle are spared from the major effects of the body's movements. The girdle accordingly can follow the movements of the body within a minimum of displacement and with a minimum of creasing and wrinkling.

15 The action zone does not need to be very wide and is generally narrower than either of the upper and lower parts of the girdle. A width of from about $\frac{1}{8}$ inch to about 3 inches is sufficient for most purposes and this width can vary in different places depending for example on the amount of give or stretch one wants to provide in particular areas. For instance the action zone can be more narrow in the area where it crosses the side of the girdle and wider underneath the buttocks and in the groin line. The holding power of the action zone material should of course be sufficient to prevent bulging out of the flesh in the action zone. In a net material made of spandex and which has its threads spaced relatively far apart, the holding power can be obtained for example by making the elastomeric threads heavier and thicker than they normally are in more closely constructed fabrics such as are used in the upper and lower parts of the girdle.

20 The drawings illustrate a preferred embodiment of my invention and are to be considered as illustrative and not limitative of my invention.

25 FIG. 1 is a three-quarter front perspective view of a panty girdle embodying my invention.

30 FIG. 2 is a three-quarter rear perspective view of the panty girdle of FIG. 1.

35 FIG. 3 is a front perspective view showing the panty girdle of FIG. 1 after the wearer has placed her left leg forward in a striding position and shows in the dotted circles the variations in the action zone material.

40 FIG. 4 is a three-quarter rear perspective view showing the panty girdle of FIG. 1 while the wearer is bending forward.

45 FIG. 5 is a view looking upward at the crotch area of a panty girdle embodying my invention.

50 FIG. 6 is a three-quarter front perspective view of an open bottom girdle embodying my invention.

55 FIG. 7 is a three-quarter rear perspective view of the girdle of FIG. 6.

60 The panty girdle 20 shown in FIG. 1 has an upper body encircling portion 22 and a lower portion comprising legs 24 and 26. Front panel 23 is stretchable in the vertical direction only. Crotch part 28 is stretchable from front to back and is made of soft material such as jersey or nylon tricot fabric. The material of the upper portion 22 may be a two-way stretch spandex cloth such as power net. The legs may also be fashioned of this fabric. The girdle may have a waistband and circumferentially elastic leg bands which encircle the legs. As previously noted the girdle in general can be made of conventional materials and follow conventional practice and for this reason it is not deemed necessary to describe the girdle of FIG. 1 in more detail as to its conventional aspects. The lines of stitching which connect the various parts together have been omitted in order to make the presentation of the invention as simple as possible. It is to be understood however that such stitching is

70 used in actual girdle specimens embodying the invention.

The FIGS. show that action zone 36 separates right leg 24 from the upper portion 22 and action zone 38 separates left leg 26 from the upper portion 22. These action zones are novel. Each may be considered as starting from the crotch region, extending in the front along the groin line outwardly and upwardly to a height in the side area at about where the femur bone of the wearer connects to the pelvis, then across the side and downwardly in the rear to just below one buttock, then horizontally beneath the buttock to the perineal region, then forwardly along the perineal region to the starting point. Each action zone is an endless band that forms a leg encircling zone. It is attached to the top edge of the leg part and the bottom edge of the adjacent upper body-encircling portion so that the leg part is not directly joined to the upper portion of the girdle at any point. This arrangement may be considered as providing a floating leg construction in which each leg is capable of independent motion without unduly affecting the upper part of the girdle and vice versa. This is particularly advantageous where the leg is made with a single layer of cloth and the upper part of the girdle is made with multiple layers and where the difference in stretchability between the parts is pronounced. The action zones can advantageously be made of spandex all-way stretch mesh fabric with open areas that are relatively uniform in size and spacing. The open network structure of such fabric allows of itself a certain amount of stretch regardless of whether the material is made of elastomeric components or not since each individual geometric FIG. formed by the threads can bend and twist quite easily. The open network also allows easier passage of air and water vapor and provides a cooler girdle.

The crotch piece 28 is elongated in shape. One end is sewn to the front of the upper body-encircling portion 22 and its other end is sewn to the rear part of the body portion 22. As is evident from FIG. 5 each side of the crotch piece 28 is adjacent to and attached to an edge of one action zone. The crotch piece is accordingly not directly joined to either leg part 24 or 26 at any point. The action zones are the sole connecting means between the legs and the rest of the girdle. This arrangement provides in effect a floating crotch piece which adds to the comfort of the wearer. The open construction has a further advantage in providing increased ventilation in the crotch area.

FIG. 3 is an example of how the action zone works. In this FIG. the wearer has taken a step forward with the left leg. The right action zone 36 has stretched quite noticeably in its lower front area as is apparent from its increased width in that locality and as shown in some detail in the enlarged fragmentary view. The left action zone 38 on the other side has contracted in the lower front as is evident from the compacted appearance of the action zone material in that area as depicted by the enlarged fragmentary view. Stresses applied to the panty girdle by the body in taking a step forward with the left leg are greatly absorbed by the stretching of the right action zone 36. Action zone 38 on the left has also reacted by contracting its width. The action zones thus stretch and expand in the areas where the stresses are augmented and contract in the areas where the stresses are reduced.

FIG. 4 is a further illustration of the way in which the action zones minimize the tendency of the girdle to become displaced from its original position. This FIG. shows a wearer bending forward. Action zones 36 and 38 respond to the imposed stresses by widening considerably in the rear. The forward parts of these action zones do not have nearly the amount of stress placed on them and consequently their original width remains practically the same. The stretched, expanded parts of action zone 36 and 38 dissipate a great deal of the force which would otherwise tend to displace the bottom edges of the legs of the girdle upwardly and the top edge of the girdle downwardly.

FIGS. 6 and 7 show my invention as embodied in an open bottom girdle. The girdle 50 has an upper part 52 which extends from the waist down to where the action zone 54 begins. It has a vertically stretchable front panel 53. The action zone

54 is about one-half inch in width. It is connected along its bottom edge to the top edge of the lower part 56 by any kind of stitching, such as zigzag, which does not interfere with the stretchability of the girdle. The lower part 56 of the girdle has 5 the usual garters 58 in the front and garters 60 in the rear for supporting the stockings.

The action zone 54 in this open bottom girdle comprises a narrow, endless band of spandex mesh which is about $\frac{1}{2}$ inch wide and more stretchable than either upper part 52 or lower part 56, both of which can be power net elastic fabric. In the front of the girdle the action zone is located so as to follow a line which may be considered to start at the bottom edge of the girdle at about the vertical midline. The action zone extends along the groin line outwardly and upwardly on one side 10 at about the height where the femur bone of the leg is connected to the pelvis. The action zone then crosses the side and slants downwardly to the rear where it runs below both buttocks in an essentially horizontal line. After passing under the buttocks it rises upwardly along the other side to a height 15 which corresponds to that part at about where the femur bone of the other leg is connected to the pelvis, and then across the side and downwardly in the front along the other groin line to the starting point.

The action zone 54 effectively separates the girdle into an 20 upper part 52 with more holding power than the lower part 56 and acts to dissipate forces in the same way as the action zones in the panty girdle. Where the force engenders an elongation of the girdle, the action zone does the elongating first and spares the upper and lower parts from undue stretching. 25 Where the force fosters a contraction in another portion of the girdle, the action zone contracts and allows the other parts of the girdle to remain essentially undisturbed.

It should be understood that benefits of the invention may 30 be obtained in girdles where the action zone substantially separates the upper portion of the girdle from the lower and is not itself circumferentially complete. For example a girdle that has my action zone construction in the groin lines in the front and under the buttocks in the rear, but lacking it in the side areas, will function and such variations are intended to be included within the scope of the claims. It is to be understood however that it is more advantageous for the action zone to be circumferentially complete as hereinbefore described.

Various changes and modifications may be made without 35 departing from the spirit and scope of the invention as defined by the claims.

I claim:

1. An undergarment for encircling the lower part of the torso comprising:
50 a first part which encircles the front, rear and side areas between at least the region defined by the waist and a portion of the hips;
a second part which encircles at least a portion of the thighs; at least one of said parts having the ability to elongate and recover in at least one direction;
and a third part which acts as an action zone and which substantially separates said first and second parts from each other;
said action zone undergarment overlying the body at least in an area where the femur bone connects with the pelvis, and having the ability to stretch and recover at least in the vertical direction and a greater ability to stretch in the vertical direction than said first and second parts; and
said action zone substantially encircling the body and extending circumferentially across the front of said garment along a line which lies along the groin area; angularly laterally along the side areas of said garment and rearwardly along a line below and substantially in juxtaposition to the buttocks when on the wearer.
2. An undergarment according to claim 1 in which the action zone is circumferential complete and entirely separates said first part of the undergarment from said second part.
3. An undergarment according to claim 2 in which said action zone crosses the side area of the undergarment at about the height where the femur bone connects with the pelvis.

4. An undergarment as claimed in claim 1 wherein said action zone varies in width along selected areas thereof.

5. An undergarment as claimed in claim 4 wherein said width variation is in the order of about one-eighth of an inch to about three inches.

6. An undergarment as claimed in claim 1 wherein said first part and said second part stretches and recovers circumferentially along a major portion of its extend and wherein said action zone stretches and recovers in the circumferential direction at least as easily as the portions of said first and second parts adjacent said action zone.

7. An undergarment as claimed in claim 1 wherein said action zone is an open netlike material.

8. An undergarment as claimed in claim 7 wherein said first and second parts are formed of openwork materials having the ability to stretch and recover in at least one direction and the openings in said action zone are larger than the openings in said openwork materials.

9. An undergarment as claimed in claim 7 wherein said action zone is an all-way stretch mesh fabric.

10. An undergarment as claimed in claim 1 wherein said undergarment is an open girdle.

11. An undergarment as claimed in claim 1 wherein said undergarment is a panty girdle, and said second part includes two leg encircling areas.

12. An undergarment as claimed in claim 11 further including a crotch piece, said crotch piece being connected along its side edge to said action zone with said action zone spacing said crotch piece apart from each of said leg encircling areas.

13. An undergarment as claimed in claim 1 wherein: said first part includes; a front panel adapted to vertically elongate and recover; and laterally extending side panels adapted to elongate and recover in substantially all directions; said side panels joined along a vertical medial

line at the rear of said undergarment; said second part includes two leg encircling areas, each of said leg encircling areas adapted to elongate and recover in substantially all directions;

said third part defining said action zone is adapted to elongate and return in substantially all directions, with the ability to elongate in the vertical direction greater in said action zone than in said first and second parts and the ability to elongate horizontally substantially equal to the elongation of adjacent portions of said first and second parts;

said action zone crossing the side area of said undergarment at about the height where the femur bone connects with the pelvis; and

a crotch piece, said crotch piece being connected along its side edge to said action zone with said action zone spacing said crotch piece apart from each of said leg encircling areas.

14. A panty girdle comprising:
a body portion adapted to encircle the front;
rear and side areas between at least the region defined by
the waist and a portion of the hips;

a pair of leg encircling portions;
a crotch portion wherein said crotch portion is spaced apart from each of said leg encircling portions by a meshlike stretchable material having the ability to elongate and recover in substantially all directions;
said meshlike material joined along one of its edges to an edge of said crotch portion and along its other edge to its associated leg encircling portions; and
said meshlike material extending completely circumferentially about its respective leg portions.
